CLAIM

The ornamental design for a knob for a lid of a pot, as shown and described.

DESCRIPTION

FIG. 1 is a perspective view of the knob for a lid of a pot showing my new design;

FIG. 2 is a top plan view thereof;

FIG. 3 is a bottom plan view thereof;

FIG. 4 is a rear elevational view thereof;

FIG. 5 is a right side elevational view thereof;

FIG. 6 is a front elevational view thereof;

FIG. 7 is a left side elevational view thereof;

FIG. 8 is a left side elevational view thereof, the broken line showing of a pot lid is environmental only and forms no part of the claimed design; and,

FIG. 9 is a top plan view thereof, the broken line showing of a pot lid is environmental only and forms no part of the claimed design.
